[57] CLAIM

The ornamental design for an apartment building or similar article, as shown and described.

DESCRIPTION

FIG. 1 is a front elevational view of an apartment building or similar article according to my invention;

FIG. 2 is a rear elevational view thereof;

FIG. 3 is a side elevational view thereof;

FIG. 4 is an elevational view of the side opposite to that shown in FIG. 3;

FIG. 5 is a top plan view on a relatively reduced scale.

FIG. 1

FIG. 2

FIG. 3

FIG. 4
